William R. Stevens of New York City
Letters Patent

The Schedule follows to show Letters Patent and making
part of the same containing a description in the words of
the said William R. Stevens himself of his improvement
in the machine for rolling Dough & cutting Crackers & Biscuits.

To all to whom these presents shall come or may concern.

C. I. William R. Stevens of the City and County of New York
in the State of New York, send greeting,

Be it known that I, the said William R. Stevens, have
invented and applied a new and useful improvement in the
construction of machinery for rolling and cutting of Crackers and
biscuit, and that the following is a full and accurate description
of the construction and operation of the said machinery as inven-
ted and improved by me. A perpendicular frame made of four
posts, each post being about eight inches wide and six inches
thick and about twelve feet high to be made of either wood or iron
or other durable material. To this frame are to be fixed four hor-
izontal rollers made of any suitable material to roll the dough to de-
sired thickness. Of double an additional number of rollers may
be used. These rollers to be connected by cog wheels, with a common
cog wheel on a running pinion attached to the frame, and having a
fly wheel connected to give motion to the machinery. Of the machinery be-
ing used for this purpose a frame is to be placed where
the fly wheel is running or connected with it or other suitable part
of machinery to give motion to the machinery, connected with
the above mentioned running pinion, by a cog wheel is a horizontal
shaft having three or more arms with a neck and pinion or other
means to turn the cutters on a perpendicular slide to the frame
and of which slide the cutters are secured which by falling on the
dough, cut the dough to biscuit. The dough to be carried to and

from the cutter upon an apron made of any suitable material or upon a portable table to be connected with the machinery. The cutters are to be made with clearance to clear themselves, and to be connected together in alternate rows.

What I particularly claim as an improvement is the peculiar arrangement of the above described machinery, by which the operation of rolling the dough and cutting the biscuit or crackers is connected and performed at the same time, and with the same machine. I also claim as an improvement the horizontal shaft rack or pinion by which motion is given to the cutters.

New York December 25th 1835.
